DESIGN FOR A HANDBAG FRAME OR SIMILAR ARTICLE

Salvatore Giordano, Forest Hills, N. Y.

Application June 2, 1947, Serial No. 139,395

Term of patent 14 years

(Cl. D87—2)

To all whom it may concern:

Be it known that I, Salvatore Giordano, a citizen of the United States, residing in Forest Hills, county of Queens, and State of New York, have invented a new, original, and ornamental Design for a Handbag Frame or Similar Article, of which the following is a specification, reference being had to the accompanying drawing, forming a part thereof.

Fig. 1 is a perspective view of a handbag frame or similar article showing my new design in open position,

Fig. 2 is a fragmentary detailed view of the ornamentation on one side of the handbag frame or similar article, and

Fig. 3 is a fragmentary detailed view of the ornamentation of the other side of the handbag frame or similar article.

The essential features of my design reside in the portions shown in full lines.

I claim:

The ornamental design for a handbag frame or similar article, as shown and described.

SALVATORE GIORDANO.
